UNITED STATES PATENT OFFICE

133,700

DESIGN FOR A GEM MOUNTING

Leo Granat, San Francisco, Calif.

Application November 29, 1941, Serial No. 104,401

Term of patent 7 years

To all whom it may concern:

Be it known that I, Leo Granat, a citizen of the United States and a resident of San Francisco, county of San Francisco, State of California, have invented a new, original, and ornamental Design for a Gem Mounting, of which the following is a specification, reference being had to the accompanying drawing, forming part thereof.

Figures 2 and 3 are side elevations of the mounting taken at right angles to each other.

I claim:

The ornamental design for a gem mounting, substantially as shown.

LEO GRANAT.
